UNITED STATES PATENT OFFICE.

THOMAS S. BROWN, OF POUGHKEEPSIE, NEW YORK, ASSIGNOR TO
ADRIANCE, PLATT & COMPANY, OF POUGHKEEPSIE, NEW YORK.

MOWING-MACHINE.

SPECIFICATION forming part of Letters Patent No. 750,942, dated February 2, 1904.

Application filed July 2, 1901. Serial No. 66,848. (No model.)

To all whom it may concern:

Be it known that I, THOMAS S. BROWN, a citizen of the United States, and a resident of Poughkeepsie, in the county of Dutchess and 5 State of New York, have invented a new and useful Improvement in Mowing-Machines, of which the following is a specification.

This invention relates to the coupling devices by which the inner shoe, to which the 10 finger-bar is attached, is connected with the frame of the mowing-machine.

One object of my invention is to construct these coupling devices in such manner that the shoe and finger-bar can be tilted to adjust 15 the front edge of the cutter mechanism up or down while holding the finger-bar firmly against backward sagging at the outer end.

Another object of my invention is to provide simple means for adjusting the outer end 20 of the finger-bar forwardly or backwardly, as may be necessary to maintain the finger-bar in its desired position.

Another object of my invention is to provide the coupling-head at the grainward end 25 of the coupling-bar with a forward extension, which guides the tilting head, to which the shoe is hinged, and which may be provided with a leading-wheel when a short shoe is used or be without a wheel when a long shoe 30 is used.

In the accompanying drawings, consisting of three sheets, Figure 1 is a sectional side elevation of a mowing-machine provided with my improvements. Fig. 2 is a top plan view 35 thereof. Fig. 3 is a front elevation, on an enlarged scale, of the coupling-bar and connecting parts with the front brace removed. Fig. 4 is a top plan view of these parts with the front brace in place. Fig. 5 is a sectional 40 side elevation of the inner shoe, tilting head, coupling head, and connecting parts viewed from the grainward side. Fig. 6 is a rear elevation of the inner shoe and connecting parts. Fig. 7 is a detached rear elevation of the support for the gag-lever. Fig. 8 is a cross-section in line 8 8, Fig. 7, with the gag-lever indicated in dotted lines. Fig. 9 is a vertical 45 cross-section through the pivot of the tilting head in line 9 9, Fig. 4. Fig. 10 is a longi-

tudinal sectional elevation in line 10 10, Fig. 4, looking grainward. Fig. 11 is a vertical cross-section through the adjustable eyebolt in line 11 11, Fig. 4, on an enlarged scale. Fig. 12 is a perspective view of a front extension of the coupling-head without a leading-wheel.

Like letters of reference refer to like parts in the several figures.

A represents the frame of a mowing or harvesting machine; A', the wheels; A², the gears; A³, the seat; A⁴, the pole, and A⁵ the yielding draft device arranged on the under side of the pole. B represents the hand-lever, which is mounted on the pole for operating the gag-lever at the inner end of the cutter mechanism. B' represents the auxiliary lever, which is operated by this hand-lever and connected by a chain b' with the gag-lever. C represents the tilting lever, which is mounted on the frame, and c is the rod which extends 70 forwardly from the lower end of this lever to the cutter mechanism. D represents the crank-wheel at the front end of the longitudinal shaft, from which the cutter-bar is actuated by the pitman d. F represents the finger-bar. All of these parts are of any well-known or suitable construction and arrangement.

G represents the coupling-bar, which extends transversely and downwardly in an oblique direction, as usual, from the front end 80 of the frame A toward the cutter mechanism. This coupling-bar has at its inner or stubbleward end an attaching-head G', which is provided at its rear side with a bearing g, arranged longitudinally with reference to the frame. 85 The coupling-bar is connected to the front end of the frame A by a pivot which passes through this bearing. The attaching-head G' is provided with a forwardly-projecting arm g', to which the inner end of the front brace H is 90 secured by screw-nuts h. This arm is concave on its upper side to make room for the pitman, which passes over the arm.

I represents a longitudinal coupling-head which is arranged at the outer or grainward 95 end of the coupling-bar and extends forwardly therefrom. The outer end of the front brace H is connected with the front end of this coup-

ling-head in any suitable manner—for instance, as shown in Figs. 2 and 4, by forming the brace with a rearwardly-projecting end k' , which engages in an ear k^2 , projecting from 5 the inner side of the coupling-head.

The coupling-head I is provided in line with the coupling-bar with a horizontal bearing k , which projects inwardly from the head and which connects at its inner end with curved 10 front and rear arms $k' k^2$, carrying at their inner ends an attaching-sleeve k^3 . For convenience in assembling the parts and for combining strength with lightness the coupling-bar G is formed of a tubular body, to which the 15 attaching-head G' and the attaching-sleeve k^3 of the coupling-head are secured by pressing these parts upon the tubular body. These connections may, however, be effected in any other suitable manner. The curved arms k' 20 and k^2 form, in connection with the bearing k and the attaching-sleeve k^3 , an open frame between the outer end of the coupling-bar and the coupling-head I. The rear arm k^2 is provided with a sleeve k^4 , in which the outer end of the 25 rear brace k^5 is secured. The bearing k is provided near its inner end with an eye k^6 , in which the draft-bar k^7 engages. The coupling-head I is concave on its under side to make room for the outer portion of the pitman. In 30 its normal position the coupling-bar inclines grainward and the bearing k stands horizontally.

L represents a tilting head yoke or plate, which is arranged against the outer side of the coupling-head I and to which the finger-bar is attached. This tilting head is connected at its rear end with the coupling-head by a transverse pivot l , turning in the bearing k , so that by tilting the head on this pivot the 35 front end of the head is swung up or down. The finger-bar partakes of this tilting movement of the tilting head, whereby the front edge of the cutter mechanism is raised or lowered, thereby raising or lowering the line of 40 cut accordingly.

The pivot l , by which the tilting head L is attached to the coupling-head, extends inwardly beyond the bearing k into the open space between the arms $k' k^2$, where the pivot 45 50 carries a tilting standard or arm l' , to which the front end of the rod c is attached, which connects with the lower end of the tilting lever C. The pivot l is preferably tubular to reduce its weight.

M represents the inner shoe, to which the finger-bar is secured, as usual. This shoe is hinged to the tilting head by pivotal or hinge connections arranged lengthwise of the machine, so that the outer end of the finger-bar 55 60 can rise and fall in operation and can be folded up when not required for use. These hinge connections are constructed as follows:

n represents a longitudinal bearing which is formed on the outer side of the tilting head 65 L near the rear end thereof, and n' represents

perforated lugs formed on the rear portion of the shoe and straddling the bearing n , to which they are connected by a pintle n^2 .

O represents an eyebolt secured to the front portion of the tilting head and engaging between perforated lugs o' on the front portion of the shoe, to which the eyebolt is connected by a pintle o^2 , arranged in line with the pintle n^2 . The eyebolt is screwed into a threaded socket o^3 which is formed on the 75 tilting head and in which the eyebolt is adjustable toward or from the tilting head. The eyebolt is preferably clamped in its adjusted position by a jam-nut o^4 . By screwing the eyebolt into the socket the outer end of the 80 finger-bar is forced forwardly, whereby any sagging of the outer end arising from wear or looseness of the parts can be taken up.

P represents the gag-lever, which bears with its outer end upon the heel p of the shoe M 85 and is connected at its inner end to the chain b' , operated from the hand-lever B, as usual. In order to enable the gag-lever to retain its position relative to the shoe as the latter and the finger-bar are tilted on the pivot l , the gag-lever is pivoted to a support which is carried 90 by the tilting head L and partakes of the tilting movement of the same. This support is preferably formed by a bar p' , which extends outwardly from the tilting standard l' and is 95 provided at its outer end with a stud p^2 , which engages in an eye p^3 , formed on the tilting head L above its pivot l . The bar p' is preferably cast in one piece with the standard l' , and the latter is secured by a pin p^4 or other 100 suitable fastening to the inner end of the pivot l after the stud p^2 has been inserted in the eye p^3 , whereby these parts are firmly secured together. The bar p' is provided with an overhanging ear p^5 , forming, with the bar, 105 a double support for the pivot p^6 of the gag-lever, Figs. 6 to 8.

The front end of the coupling-head I is provided with a guide or keeper q , which overlaps the front end of the tilting head and guides the latter as it moves up or down and holds the same in contact with the coupling-head against the rearward pressure which is caused in the cutter mechanism by the resistance of the grass or grain. This guide q is 110 secured to the front portion of the coupling-head by bolts q' , so as to be detachable, and is preferably formed, as shown in Figs. 4, 5, and 115 10, on a front extension Q of the coupling-head. The leading-wheel R is mounted on this extension and is preferably vertically adjustable thereon for high or low cut by providing a vertical series of openings r for the stud r' , on which the wheel turns, as shown in Fig. 10, or in any other suitable manner. In 120 Fig. 12 is represented a guide extension Q' without a wheel, which is substituted for the wheeled extension when a long-nosed sled-shaped shoe is employed. Extensions of different length and provided with wheels of 125 130

different diameters may be provided for adapting the device to shoes of different forms or sizes.

The coupling-head at the grainward end of the coupling-bar is firmly held in position by the coupling-bar, the front brace, and the push-bar or rear brace. The front brace holds the front end of the coupling-head securely against the backward pressure of the finger-bar and forms, with the coupling-bar, the attaching-head, and the coupling-head a very strong and rigid movable frame for supporting the cutter mechanism. The backward sagging of the outer end of the finger-bar, resulting from looseness of the parts or other causes, is readily corrected by means of the adjustable connection at the front end of the tilting head. The tilting head is firmly connected to this coupling-head at its rear end by the long pivot and at its front end by the guide or keeper and holds the shoe and finger-bar securely and enables the same to be tilted without allowing the outer end of the finger-bar to sag. The gag-lever partakes of the tilting movement of the tilting head and retains its position relative to the shoe in all positions of the latter.

The transverse pivot on which the tilting head rocks is arranged about in line with the heel or rear edge of the finger-bar, and the fingers are located in front of this pivot. The points of the fingers and the cutters are therefore located at a considerable distance in front of the pivot-line and rise or fall considerably in tilting the head. The plane or level of the cut can therefore be considerably raised or lowered by tilting the head and can be adjusted closely to the ground or at a considerable height above the ground.

40 I claim as my invention—

1. The combination of a coupling-bar, a coupling-head rigidly secured to the grainward end thereof, a tilting head connected at its rear end to the rear end of said coupling-head by a transverse pivot, means for guiding the front end of the tilting head in its vertical movement, a shoe attached to said tilting head, and a finger-bar secured to said shoe and having its rear edge arranged adjacent to said pivot and its fingers arranged forwardly of the pivot, whereby the points of the fingers are located at a considerable distance in front of said pivot and are raised or lowered by tilting the head without materially changing the elevation of the rear edge of the finger-bar, substantially as set forth.

2. The combination of a coupling-bar, a coupling-head secured to the grainward end thereof, a brace arranged in front of the coupling-bar and secured to the front portion of said head, a tilting head arranged on the grainward side of said coupling-head and pivoted at its rear end to the same, a guide arranged on the front end of said coupling-head, and engaging the front end of said tilting head,

and a shoe and finger-bar carried by said tilting head, substantially as set forth.

3. The combination of a main frame, a coupling-bar, a coupling-head secured to the grainward end thereof, a push-bar arranged in rear of the coupling-bar and connecting the latter with the main frame, a brace arranged in front of the coupling-bar and secured to the front portion of said head, a tilting head arranged on the grainward side of said coupling-head and pivoted thereto, and a shoe and finger-bar carried by said tilting head, substantially as set forth.

4. The combination of a main frame, a coupling-bar provided at its inner end with an attaching-head which is pivoted to the main frame, a coupling-head secured to the grainward end of the coupling-bar, a brace arranged in front of the coupling-bar and connecting said attaching-head to said coupling-head, a tilting head pivoted to said coupling-bar, and a shoe and finger-bar carried by said tilting head, substantially as set forth.

5. The combination of a coupling-bar, a coupling-head arranged at the grainward end thereof, an open frame interposed between the coupling-bar and the coupling-head, a pivot-bearing extending through said coupling-head into said open frame, a tilting head having its pivot arranged in said bearing, a tilting post arranged in said open frame and secured to said pivot, and a shoe and finger-bar carried by said tilting head, substantially as set forth.

6. The combination of a coupling-bar, a coupling-head arranged at the grainward end thereof, a tilting head pivoted to said coupling-head, a shoe and finger-bar carried by said tilting head, a gag-lever, and a gag-lever support which is attached to said tilting head and partakes of its tilting movement, substantially as set forth.

7. The combination of a coupling-bar, a coupling-head secured to the grainward end thereof and provided with a pivot-bearing, a tilting head having its pivot extending through said bearing, a tilting post secured to said pivot on the inner side of said bearing, a support for the gag-lever secured to said post and said tilting head, a gag-lever pivoted to said support, and a shoe and finger-bar carried by said tilting head, substantially as set forth.

8. The combination of a coupling-bar, a coupling-head secured to the grainward end thereof, a tilting head pivoted to said coupling-head, a shoe connected at its rear end to said tilting head, a laterally-adjustable device connecting the front end of said shoe to said tilting head, and a finger-bar carried by said shoe, substantially as set forth.

9. The combination of a coupling-bar, a coupling-head secured to the grainward end thereof, a tilting head pivoted to said coupling-head, a shoe connected at its rear end to

said tilting head by a longitudinal pivotal joint, a longitudinal pivotal joint connecting the front portion of said shoe with said tilting head and consisting of a screw-eye arranged in a threaded socket on the tilting head and ears on the shoe to which said eye is pivoted, and a finger-bar carried by said shoe, substantially as set forth.

10. The combination of a coupling-bar, a coupling-head secured to the grainward end thereof and projecting forwardly therefrom, a tilting head connected at its rear end to the rear end of said coupling-head by a transverse pivot, a front extension secured to said coupling-head and provided with a guide which engages the front end of said tilting head, a leading-wheel mounted on said front extension, a shoe attached to said tilting head, and a finger-bar secured to said shoe and having

its fingers arranged in front of said transverse pivot, substantially as set forth.

11. In a device of the class described, the combination of the yoke having a screw-threaded socket with a threaded stem mounted in said socket, and means for connecting said stem with the shoe.

12. A yoke having a screw-threaded socket in combination with a screw-threaded stem mounted in said socket and having a tubular cross-piece at its outer end, and a bolt connecting the same with the shoe of a mowing-machine.

Witness my hand this 27th day of June, 1901.

THOMAS S. BROWN.
